Primary Examiner—Carol Rademaker

(74) Attorney, Agent, or Firm—Banner & Witcoff, Ltd.

(57) **CLAIM**

The ornamental design for a bottle, as shown and described.

DESCRIPTION

FIG. 1 is a top, front, and right side perspective view of a first Embodiment of the bottle embodying the new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan thereof;

FIG. 7 is a bottom plan view thereof; and,

FIG. 8 is a top, front, and right side perspective view of a second embodiment of the bottle embodying the new design, all views being identical to those of Embodiment 1 except that the unclaimed pour spout is now included as a part of the claimed design.

The broken lines shown in FIGS. 1-6 are for illustrative purposes only and form no part of the claimed design.

1 Claim, 4 Drawing Sheets

Fig. 1
